INVENTOR

BY Victor J. Evans

ATTORNEY

WITNESS:

UNITED STATES PATENT OFFICE.

JOEL P. HARPER, OF BLUEFIELD, WEST VIRGINIA.

UNIVERSAL VALVE-SPRING COMPRESSOR.

Application filed July 18, 1921. Serial No. 485,625.

To all whom it may concern:

Be it known that I, JOEL P. HARPER, a citizen of the United States, residing at Bluefield, in the county of Mercer and State 5 of West Virginia, have invented new and useful Improvements in Universal Valve-Spring Compressors, of which the following is a specification.

This invention relates to means for compressing the springs of valves of internal combustion motors, to permit the assembling and disassembling of the valve unit, the general object of the invention being to provide a device which can be used for compressing the springs of all "valve in the head" motors including the type where the valve unit is carried by a cage.

Another object of the invention is to make the device of few parts which are so arranged that the device is extremely simple in operation and can be manufactured to sell at low cost.

A further object of the invention is to make the parts adjustable so that the device can be used on heads or cages of different widths and different heights.

This invention also consists in certain other features of construction and in the combination and arrangement of the several 30 parts, to be hereinafter fully described, illustrated in the accompanying drawings and specifically pointed out in the appended claims.

Figure 1 is a perspective view of the invention.

Figure 2 is a sectional view showing the same in use.

Figure 3 is a sectional detail view through the spring engaging member and the handle.

As shown in these views the device comprises a base 1, an upright 2, a handle 3, pivotally and adjustably connected with the upright, and the spring engaging member 4 45 which is slidably mounted on the handle. I prefer to form the base 1 and upright 2 from a single strip of material which is bent at right angles to form the upright. The major portion of the upright is of channel 50 shape in cross section, this shape being given to the upright by notching the edges of the strip, as at 5, and bending the side edges at right angles to produce the flanges 6. These flanges are each provided with a plurality of holes 7 for receiving the pivot pin 8 which hinges the handle 3 to the upright.

The handle is adjusted in relation to the base by placing the pin 8 in any one of the pairs of holes 7. The handle 3 is formed of a strip of material looped upon itself with its extremities perforated to receive the pivot pin 8. The member 4 is also formed of a strip of metal bent into U-shape to embrace the handle and with its extremities bent upwardly, as at 4', to engage the inner faces 65 of the limbs of the handle. Thus the member is slidably connected with the handle. The bight of member 4 is provided with a cup-shaped depression 9 in its under face which has a hole 10 in its center. This depression is adapted to receive the upper end 70 of the spring 11 of the valve 12, the stem of the valve passing through the opening 10. An opening 13 is formed in the base for receiving the head of the valve and the walls 75 of this opening are beveled so as to provide a seat for the valve, as shown in Figure 2. This seat is especially adapted for removing springs from valves of the Buick type where the valve is arranged in a cage.

It will be seen from the above that the spring of the valve can be easily and quickly depressed for removing or replacing the pins which hold the spring in place on the stem. The cup-shaped depression 9 acts to center 85 the spring and by having the member 4 slidably mounted on the handle and the handle adjustable vertically on the upright the device can be used with various types and sizes of motors. The parts are so arranged that there is no danger of the spring slipping and causing parts to fly about and thus injure the operator.

It is thought from the foregoing description that the advantages and novel features 95 of my invention will be readily apparent.

I desire it to be understood that I may make changes in the construction and in the combination and arrangement of the several parts, provided that such changes fall within the scope of the appended claims.

What I claim is:—

1. A device of the class described comprising a base, an upright connected therewith, a handle adjustably and pivotally connected 105 with the upright and a spring engaging member slidably mounted on the handle.

2. A device of the class described comprising a base, an upright connected therewith, a handle adjustably and pivotally connected with the upright and a spring engaging member slidably mounted on the 110

handle, said member having a cup-shaped depression therein for engaging the spring and an opening at the center of the depression for receiving the valve stem.

5. 3. A device of the class described comprising a base, an upright connected therewith, a handle adjustably and pivotally connected with said upright, a valve spring engaging member slidably mounted on the 10 handle and said base having an opening therein having beveled walls for forming a seat for a valve head.

4. A device of the class described comprising a base, an upright connected with the

base and being of channel shape in cross section, the flanges of said upright having a plurality of holes therein, a handle of U-shape, a pivot pin passing through the extremities of the handle and engaging any one of the pairs of holes in the upright, a valve spring 20 engaging member of U-shape having its limbs embracing the limbs of the handle, the bight of said member having a cup-shaped recess therein for receiving the end of the spring and an opening at the center of the 25 recess for receiving the valve stem.

In testimony whereof I affix my signature.
JOEL P. HARPER.
